UNITED STATES PATENT OFFICE.

EDWARD LARSON, OF LERDALA, SWEDEN.

SAFETY DEVICE FOR FIREARMS.

1,306,965.

Specification of Letters Patent. Patented June 17, 1919.

Application filed January 29, 1918. Serial No. 214,399.

To all whom it may concern:

Be it known that I, EDWARD LARSON, contractor, subject of the King of Sweden, residing at Lerdala, Sweden, have invented 5 certain new and useful Improvements in Safety Devices for Firearms, of which the following is a specification.

The present invention relates to improvements in safety devices for portable firearms and has for object to procure a more simple and more reliable device of that kind than has heretofore been proposed.

The invention is principally characterized by two locking members, preferably arranged 15 on opposite sides of the frame, whereby both the locking members independently of each other lock the trigger in its safety-position and are automatically and independently of each other moved from this 20 position when the arm is placed in the hands in position to be fired.

Two embodiments of the invention are shown in the accompanying drawing, wherein Figure 1 is an elevational view of a gun 25 frame to which my invention has been applied and Fig. 2 a similar view of another embodiment. Fig. 3 shows a detail.

With respect of the embodiment shown in Fig. 1 1 denotes the usual trigger, which is 30 pivoted to a pin 2. The two locking members consist, in conformity with the embodiment shown, of two levers 3, 4 and 5, 6 whereof one 3, 4 is arranged on the upper side of the frame and is formed as a bell- 35 crank lever, the one arm 3 of which locks the trigger, while the other lever 5, 6 is arranged on the underside of the frame and in the same way locks the trigger. The arms 4, 6 intended to be operated by hand prefer- 40 ably extend outside the stock through slots or openings in the same as shown in the drawing.

The levers or locking members 3, 4 and 5, 6 are preferably actuated in known way by 45 springs.

As shown in the drawing the locking members are arranged in such a way so as to move automatically from their safety-position when the arm is placed in position to be fired. Hereby the trigger will be unlocked in order that the same may be operated in the usual way in firing. Firstly the locking

member 5, 6 is operated, whereby the arm 5 unlocks the trigger, whereupon the locking member 3, 4 is operated, whereby its arm 3 55 will be placed directly above a recess 7 in the trigger so as to allow the free movement of the latter.

According to the second embodiment the same differs from that already described 60 only in that the one arm 4 of the locking member 3, 4 is divided into two or several parts 4 and 4^a, movably connected with each other. Said movable connection may be of 65 convenient kind. I have, however, found that the arrangement is performed in the best way by placing a pivot 8 on one of the parts, while the other part is provided with a slot or such like 9, being oblong for the 70 purpose mentioned hereinafter.

The free end of the arm 4^a is pivoted to a pin 10 and the locking member is in usual way pivoted to a pin 11. It is obvious that the part extending outside the frame is 75 moved in such a way in operating the arm 4^a that the arm 3 of the locking member unlocks the safety-device, whereby the slot 9, as mentioned above, must be oblong because the distance between the points 10 and 11, 80 counted along the parts 4, 4^a of the arm, is extended.

Said arrangement is provided for the purpose that the part of the locking member which extends outside the frame may be arbitrarily moved backward from the pivot of 85 the said member.

It is to be observed that if the arm 4, 4^a is situated in the vertical middle plane of the frame, then must the same be provided 90 with a slot or such like in order to allow the usual screw 12 to pass.

The last described modification works in the same way as the first embodiment.

It must further be observed, that the other arm 3 of the locking member 3, 4 is placed between two safety-levers 13, said levers being pivoted on the pin 11. The arm 3 locks the triggers 1 and 1^a (Fig. 3), while the levers 13 lock the sears 14. The arm 3 can 100 be moved into the safety-position independent of the locking levers 13 and remain in said position. The arm 3 and the locking levers 13 are, however, at the same time arranged in such a way as to be simultaneously 105

moved from their safety-position. The arm 3 is for that purpose provided with a catcher 15 which by the movement of the arm from the safety-position unlocks the sears 14 (Fig. 3).

I claim:—

1. A safety device for fire arms including a frame, a pair of locking members arranged on opposite sides of said frame, a trigger, 10 said locking members holding said trigger, independent of each other, and means for releasing said locking members from said trigger.
2. A safety device for fire arms including 15 a frame, a pair of locking members of bell-crank shape pivotally secured one to each side of said frame, a trigger, said locking members holding said trigger independently

of each other, and means for releasing said locking members from said trigger. 20

3. A safety device for fire arms including a frame, a pair of locking members of bell-crank shape pivotally arranged on opposite sides of said frame, the arm of one bell crank being divided into two parts, a trigger, 25 said locking members holding said trigger independently of each other, and means for releasing said locking members from said trigger.

In testimony whereof I affix my signature 30 in presence of two witnesses.

EDWARD LARSON.

Witnesses:

ALF. GUSTAFSSON,
IVEN LARSSON.
